UNITED STATES PATENT OFFICE.

DANIEL J. McGEEHIN, OF WEST HAZLETON, PENNSYLVANIA.

HYDRAULIC WATER PIPE CLEANER.

Application filed February 19, 1926. Serial No. 89,400.

This invention relates to a hydraulic water pipe cleaner, which is adapted to pass through a water main, sewer or the like, and to remove all deposits which adhere to the 5 inside thereof, leaving the pipe clear so that its full capacity may be utilized.

The principal object of the invention is to provide an improved device of this character which, when placed in the pipe, will be propelled through the same by the pressure of 10 the water therein, and which has a relatively rotatable part also actuated by the water pressure to scrape or brush the inner surface of the pipe.

15 The invention also includes various features of construction, which facilitate the progress of the device through the pipe, and its automatic operation.

20 The construction and operation of the invention and the advantages thereof will be more fully explained in connection with the accompanying drawings, which illustrate one embodiment thereof, and in which

Figure 1 is a side elevation.

25 Figure 2 is a central longitudinal section. Figure 3 is a transverse section taken on the line 3—3 of Figure 2.

Figure 4 is a transverse section taken on the line 4—4 of Figure 2.

30 Figure 5 is a transverse section taken on the line 5—5 of Figure 2.

Figure 6 is a central longitudinal section through the shell, detached.

35 Figure 7 is a side elevation of the double turbine which is adapted to be housed within the shell.

Figure 8 is a transverse section taken on the line 8—8 of Figure 2.

40 The device, which constitutes the subject matter of my invention, comprises an approximately cylindrical shell or housing 10, having outwardly inclined channels 11 in its periphery, and in these channels are mounted spurs 12, having teeth 13 adapted 45 to drag against the inner surface of the pipe.

A central sleeve 14 is disposed centrally of the shell 10, and is integrally connected therewith by webs 15. A hub 16 is secured within the sleeve 14.

50 The front end of the sleeve 14 is formed with a flange 17, in front of which a turbine 18 is rotatably mounted on the reduced, forwardly extending portion 19 of the hub. The front portion of the turbine is enclosed 55 by a housing extension 20, which is secured

on the threaded reduced portion 21 of the shell 10, and is provided with outwardly directed passageways 22 through which the water passes as it leaves the turbine 18. Inside of the passageways 22, the housing extension 20 is formed with an annular seat 60 23 for receiving a second turbine 24, which is secured to a reduced threaded boss 25 extending forwardly from the turbine 18. The turbine 24 is formed with a collar 26, which extends forwardly from the housing extension 20, and through which the water passes as it leaves the turbine. This collar has diametrically opposed pins 27, which are secured to and extend outwardly therefrom, 65 and on which a ring 28 is pivotally mounted. A second ring 29, outside of the ring 28, has pins 30 secured to and extending inwardly therefrom into the ring 28 midway between the pins 27, so that the outer ring 29 has a 70 universal connection with the collar 26.

75 Bars 31 are secured to and extend forwardly from the ring 29, and the forward ends of the bars are curved inwardly and secured to a smaller ring 32. Bristles 33, extending outwardly from the bars 31, are adapted to engage the inside of the pipe as the cleaner passes therethrough. Resilient strips 34 are secured to the ring 29, and extend forwardly therefrom midway between the bars 31, and are formed with outwardly disposed scraper blades 35, the edges of which taper slightly toward the front end. The front end of each strip 34 has a slotted connection 36 with the front ring 32, so as to permit the strips to yield inwardly whenever the blades 35 encounter unusual resistance.

80 The head 37 is secured to the reduced, forwardly projecting end portion of the hub 16, and is provided with a forwardly and outwardly flared surface 38 for directing the water toward the blades 35 as it leaves the turbine 24, so as to wash away the material dislodged by the blades in their rotation.

85 A block 39 is connected by a pivot bolt 40 to the front end of the head 37, and a spindle 41 is pivotally connected to the forward end of the block 39 by a pivot bolt 42, which extends transversely to the pivot bolt 40. Thus, the spindle 41 has a universal 90 pivotal connection with the head 37, so as to permit it to adapt itself to bends in the pipe as the cleaner passes therethrough. The front end of the spindle 41 extends 95 through and considerably beyond the ring 100 105 110

32, and has blades 43 which resiliently engage the inside of the pipe and aid in guiding the cleaner therethrough.

The rear end of the shell 10 is formed 5 with a reduced threaded portion 44 for receiving a clamping ring 45, which is adapted to clamp a packing ring 46, so as to prevent any appreciable amount of water from 10 passing through the pipe outside of the shell 10. The extension 20 may also be provided with a threaded reduced portion 47 for receiving a clamping ring 48 to clamp a secondary packing ring 49.

In using the pipe cleaner, it is to be understood that the pipe to be cleaned is cut in 15 two places. The hydraulic cleaner is then inserted into the pipe through the first cut, and is carried along by water pressure until it reaches the second cut. During its 20 travel, it is guided by the blades 43 and the shell 10, and the teeth 13 carried by the latter drag against the inner face of the pipe, retarding the travel of the cleaner while the water passes through the turbines 25 18 and 24, rotating the same, and thereby rotating the scraper blades 35 and brushes 33. As fast as the scraper blades and brushes dislodge material from the inside of the pipe, it is washed away by the action of 30 the current, which, in leaving the turbine 24, is diverted outwardly by the head 37. As fast as the inner surface of the pipe is cleaned, the cleaner will be automatically carried forward by the pressure of the 35 water, and the scraper blades and brushes will gradually work forward until the pipe is cleared throughout its entire length, and the cleaner arrives at the point where the second cut has been made.

40 While I have shown and described in detail the preferred form of the invention, it is to be understood that various modifications may be made in the structural details thereof without any material departure from 45 the salient features of the invention as expressed in the claims.

What is claimed is:

1. In a water pipe cleaner, the combination with a housing, of a hub secured to the 50 housing and disposed centrally thereof, a spindle flexibly connected to the front end of the hub and having means at its forward end for engaging the wall of the pipe and guiding the cleaner in its progress through 55 the pipe, a turbine rotatably mounted on the hub, and means in front of the housing and rotatable with the turbine to clean the inner surface of the pipe.

2. In a water pipe cleaner, the combination 60 with a housing, of a hub secured centrally thereof, a spindle flexibly connected to the front end of the hub and having means at its forward end for engaging the wall of the pipe and guiding the cleaner in 65 its progress through the pipe, spurs mount-

ed peripherally of the housing and having teeth to engage the wall of the pipe, thus constituting a drag for the cleaner and preventing rotation of the housing while traveling through the pipe, a turbine rotatably mounted on the hub, and means in front of the housing and rotatable with the turbine to clean the inner surface of the pipe.

3. In a water pipe cleaner, the combination with a housing, of a sleeve disposed centrally thereof, webs integrally connecting the sleeve to the housing, a hub secured in the sleeve and projecting forwardly therefrom, a turbine rotatably mounted on the hub, a spindle flexibly connected to the front end of the hub and having means at its forward end for engaging the wall of the pipe and guiding the cleaner in its progress through the pipe, spurs mounted peripherally of the housing and having teeth to engage the wall of the pipe, thus constituting a drag for the cleaner, and means in front of the housing and rotatable with the turbine to clean the inner surface of the pipe.

4. In a water pipe cleaner, the combination with a housing, of a turbine rotatably mounted within the housing, spurs mounted peripherally of the housing and having teeth to engage the wall of the pipe, thus constituting a drag for the cleaner, a member located in front of the housing and connected with the turbine so as to rotate therewith, and cleaning elements projecting radially from said member.

5. In a water pipe cleaner, the combination with a housing adapted to be propelled through the pipe by water pressure, of a turbine rotatably mounted within the housing and adapted to be rotated by water passing through the housing, a ring in front of the housing and connected to the turbine to rotate therewith, bars secured to and extending forwardly from said ring, another ring connecting the front ends of said bars, brushes carried by said bars and engageable with the inner surface of said pipe, flexible strips between the brushes, and scraper blades carried by said strips, said strips being secured to the rear ring and having slotted connections with the front ring.

6. In a water pipe cleaner, the combination of a housing through which the water may pass, a turbine rotatably mounted within the housing, cleaning elements in front of the housing and connected with the turbine to rotate therewith, the outer face of said housing being formed with peripheral channels inclined outwardly, and spurs mounted in said channels and constituting a drag for the cleaner as it is carried through the water pipe.

7. In a water pipe cleaner, the combination of a housing through which water may pass, a hub secured centrally of the housing and having a peripheral flange leaving a

space for the water to pass between the edge of the flange and the wall of the housing, a turbine rotatably mounted on the hub in front of the flange, an extension secured to the housing in front of said turbine and having diverging passageways receiving the water from said turbine, and a second turbine within the front portion of the housing

extension and secured to the first turbine and receiving the water from said divergent passageways, and cleaning elements in front of the housing extension and connected to the second turbine to rotate therewith.

In testimony that I claim the foregoing as my own, I have hereto affixed my signature.

DANIEL J. McGEEHIN.
